EMBOSSED PLASTIC FABRIC OR THE LIKE

William K. Vernon, Meyer Place, Riverside, Conn.

Filed Mar. 14, 1958, Ser. No. 50,039

Term of patent 7 years

(Cl. D87—3)

FIG.2.

Fig. 1 is a fragmentary plan view of a portion of an embossed plastic fabric showing my new design, and

Fig. 2 is a sectional view taken on line 2—2 of Fig. 1.

I claim:

The ornamental design for an embossed plastic fabric or the like, substantially as shown.
